UNITED STATES PATENT OFFICE.

GEORGE MILLIKEN, OF ORANGEVILLE, ILLINOIS, ASSIGNOR OF ONE-HALF TO E. M. REESER, OF ORANGEVILLE, ILLINOIS.

STOCK SALTER.

Application filed November 25, 1921. Serial No. 517,535.

To all whom it may concern:

Be it known that I, GEORGE MILLIKEN, a citizen of the United States, residing at Orangeville, in the county of Stephenson, 5 State of Illinois, have invented a new and useful Stock Salter; and I do hereby declare the following to be a full, clear, and exact description of the invention, such as will enable others skilled in the art to which it 10 appertains to make and use the same.

The invention relates to stock salters, and has for its object to provide a device of this character comprising a pivoted receptacle pivoted mounted on a stand and having 15 one of its sides opened through which open side stock may have access to the chamber of the receptacle in which salt is disposed. Also to provide in combination with the pivoted receptacle, a vane, which vane forms 20 means whereby the open side of the receptacle is maintained by means of the wind on the leeward, thereby preventing rain from being driven into the open side of the receptacle and dissolving the salt, thereby 25 causing loss of salt or reducing the salt to a liquid which the cattle will drink, which often causes cattle to die.

A further object is to detachably secure 30 the base of the receptacle in which said receptacle pivots to a supporting stand, thereby allowing the device to be easily disassembled for repair purposes.

With the above and other objects in view 35 the invention resides in the combination and arrangement of parts as hereinafter set forth, shown in the drawings, described and claimed, it being understood that changes in the precise embodiment of the invention may be made within the scope of what is 40 claimed without departing from the spirit of the invention.

In the drawings—

Figure 1 is a vertical sectional view 45 through the upper end of the stand and the salt receptacle.

Figure 2 is a front elevation of the device.

Figure 3 is a horizontal sectional view taken on line 3—3 of Figure 1.

Referring to the drawings, the numeral 50 1 designates a stand, which stand comprises vertically disposed and spaced members 2, the upper ends of which at opposite sides thereof are connected together by means of horizontally disposed bars 3, thereby forming a rectangular shaped opening 4 in the

upper end of the stand in which is received a removable base 5. Base 5 is held within the opening 4 by means of transversely disposed bolts 6 which extend through the members 2 and through the base 5, thereby not only rigidly holding the base but at the same time holding the same in such a way that it may be easily removed. The base 5 has pivotally mounted therein a bearing sleeve 7, on the upper end of which bearing sleeve is secured by means of a bolt 8, a salt receptacle 9. During the pivotal action of the salt receptacle 9, the bearing sleeve 7 turns in the bearings 10 and 11 of the base 5, thereby reducing the friction to a minimum and allowing the receptacle 9 to be easily turned on its pivotal point. Extending upwardly from the rear side 12 of the receptacle 9 is a mast 13 to the upper end of which is pivoted at 14 the arm 15 of 75 a vane 16. Arm 15 extends substantially horizontally and in the direction of the front 17 of the receptacle 9, therefore it will be seen that wind will through the medium of the vane 16 maintain the open side 17 of 80 the receptacle 9 to leeward, and consequently prevent wind from blowing into the chamber 18 of the receptacle 9 through the opening 19 and blowing the salt from the receptacle, or blowing rain into the chamber 85 18 where it will dissolve the salt and cause damage to stock which may drink the salt water. The top 20 of the receptacle 9 is preferably inclined downwardly and rearwardly and acts as a water shed. The position of the vane 16 may be varied vertically by the supporting arm 21 which is pivoted as at 22 to the mast 13 and secured to the arm 15 by means of a pin 24 which extends through registering apertures of 90 plurality of apertures in the arm 15 and the arm 21, said apertures being designated by the numerals 25 and 26. The salt 27 is placed within the chamber 18 and is renewed from time to time as the same is consumed.

From the above it will be seen that a pivoted salting device is provided, which is simple in construction and one which may be easily dismantled for repair purposes.

The invention having been set forth what is claimed as new and useful is:—

A support for a pivoted receptacle comprising a horizontally disposed rectangularly shaped frame, opposite sides of said frame 110

forming supporting legs for the support, a horizontally disposed rectangularly shaped frame disposed within the first mentioned frame and formed from spaced rectangular shaped members, spacing strips at opposite sides of the rectangular shaped members, bolts extending through the upper ends of the sides of the first mentioned frame and the spacing strips, a bearing sleeve extending through registering apertures of the rectangular shaped members, the upper end of

said bearing sleeve being provided with a bevelled flange engaging a bevelled seat carried by the upper rectangular shaped member.

15

In testimony whereof I have signed my name to this specification in the presence of two subscribing witnesses.

GEORGE MILLIKEN.
